GAS CANNON AND METHOD OF OPERATING
SAMEEdward S. Peake, Westerville, Ohio, assignor to
The Kilgore Mfg. Company, Westerville, Ohio,
a corporation of Ohio

Application November 28, 1932, Serial No. 644,680

8 Claims. (Cl. 42—55)

My invention relates to gas cannons and in particular to a method of generating gas for and firing a gas cannon.

It is the object of my invention to provide a measured pellet or cartridge of gas forming material, such as carbide, of known gas generating quality; to apply a small measured quantity of water only sufficient for the generation of gas for one firing of the cannon; to inject into the cannon an additional supply of air behind the ammunition, which is in airtight engagement with the cannon, to thereby thoroughly mix and carburet the air, and then to ignite, preferably at the end of such air injection and mixture, the combined gases in order to get the greatest result in firing the projectile with the minimum expenditure of carbide.

It is my object to provide a rich mixture of carbide gas which can be rendered highly explosive by carburetion due to the introduction of fresh air after the generation of the gas, such air being introduced under pressure into the gas cannon.

It is my object to use a projectile that is resilient or has a resilient covering.

It is a further object to provide a carbide pellet from which repeated charges of gas can be extracted by applying successive amounts of measured quantities of water, thereby reducing the amount of water to the minimum and enabling the removal of hydrate from the carbide pellet between applications of water, as desired.

Figure 1 is an elevation of the cannon from the side of the mixture applying apparatus.

Figure 2 is a side elevation from the side of the ignition apparatus.

Figure 3 is a section on the line 3—3 of Figure 2.

Figure 4 is a rear elevation of the cannon.

Figure 5 is a perspective of a typical disk or pellet form of carbide used for forming the gas.

It will be understood that this drawing is purely diagrammatic. The mortar or cannon may be made of any desired form so long as the essential steps of my method are employed and so long as the essential parts are utilized for the practice of the method.

Referring to the drawing in detail, 1 is a cannon or mortar and base 2 upon which is mounted a detachable breach block 3 threaded at 4 to the base of the cannon. The cannon is provided with a diverging Y member 5 having a threaded closure 6 within which is located a pellet 7 of carbide. While a granular form may be employed, I desire to use preferably a compressed pellet of carbide, preferably with a binder such as sulphur and sugar, so that a gas forming body of uniform

quantity will be employed in order to insure a uniform amount of gas upon the application of one or more drops of water. The water is measured by controlling the admission of water through the rubber pipe 8 by the valve clamp 9 drop by drop. A stopper 10 is mounted in a water passageway 11 which communicates directly with the Y member 5 so that the drops of water can drop upon the pellet 7. The gas thus generated makes its exit through the opening 12 into the interior of the cannon 13. Air is injected under pressure, as with a bicycle pump or any other source of compressed air, through the valve 14. Due to the pressure of injection the air causes a considerable turbulence as it enters into the interior of the cannon, thoroughly mixing the gas. The gas is prevented from escaping by the resilient projectile ball 15 which is held in position by the overlapping restricted shouldered throat 16 of the cannon. At the time you have the maximum oxygen and maximum pressure applied in the cannon, I simultaneously apply the spark at the termination of the stroke of the air pump delivering the air.

The firing of the spark for this purpose may be automatically controlled simultaneously with the termination of the injection of air or they may be independently timed.

This spark device may consist of a flint 17 spring-pressed by the spring 18 and sleeve 19 and a corrugated steel 20 actuated by the finger piece 21, shaft 22 and spring 23 working against the shoulder 24 and the sleeve 25. Any desired form of ignition mechanism may be employed. Upon igniting the gas, the resilient projectile ball 15 is driven outwardly with great force and to a considerable distance.

I desire to comprehend within my invention such modifications as may be embraced within my claims and the scope of my invention.

Having thus fully described my invention, what I claim as new and desire to secure by Letters Patent, is:

1. In a method of producing and firing gas in a gas cannon, providing a measured gas forming material in the cannon enclosure, yieldingly sealing the enclosure, applying a measured quantity of water on the gas forming means, injecting an additional quantity of air into the enclosure to further carburet the air therein, and igniting the mixture to blow out the seal.

2. In a method of producing and firing gas in a gas cannon, providing a measured gas forming material in the cannon enclosure, yieldingly sealing the enclosure, applying a measured quantity

of water on the gas forming means, injecting an additional quantity of air into the enclosure to further carburet the air therein, and igniting the mixture to blow out the seal simultaneously with the completion of the injection of the additional quantity of air.

3. In combination, a gas cannon employing a measured quantity of gas forming material, means for supporting a gas forming material remote from and in communication with the cannon, means of applying a measured quantity of water thereto, a resilient projectile mounted in the mouth of said cannon, means of igniting the gas so formed, and means of injecting an additional quantity of air into the cannon under pressure after the gas has started to form, and means for igniting the gas so formed.

4. In combination, a cannon body, a diverging communicating chamber for the forming of gas, means to support a gas forming pellet therein, means of introducing water drop by drop onto said pellet, means of firing the gas thus generated when it is delivered into the cannon, and resilient means for retaining the pressure of gas thus generated in the cannon until so fired.

5. In combination, a cannon body, a diverging communicating chamber for the forming of gas, means to support a gas forming pellet therein, means of introducing water drop by drop onto said pellet, means of firing the gas thus generated when it is delivered into the cannon, resilient means for retaining the pressure of gas thus generated in the cannon until so fired, and

means for injecting an additional quantity of outside air into the cannon after the gas has been thus generated and immediately prior to firing.

6. In combination, a cannon for using a compressed pellet of carbide, means of applying water drop by drop on the pellet to form a measured charge of gas, a resilient closure member for the cannon to confine the gas so generated, means to fire the gas, and means to inject under pressure an additional quantity of air into the gas thus formed prior to firing to carburate the gas.

7. In combination, a vertically disposed mortar having an open top with an overhanging lip, a resilient ball projectile engaged in said mortar beneath said lip, a diverging chamber adjacent the bottom of said mortar for receiving a carbide pellet, means mounted thereon of admitting water drop by drop thereto, means in the mortar for admitting air under pressure, and means in the mortar for firing the mixture of gas and air within the mortar.

8. In combination, a base plate, a breach block mounted thereon, a detachable mortar mounted on said breach block having a diverging chamber, a detachable head on said chamber for admitting a gas forming material thereto, means of supplying and controlling the admission of liquid in said chamber, a firing mechanism on the side of said mortar above said chamber, a valve for admitting air under pressure on said mortar adjacent said firing mechanism.

EDWARD S. PEAKE.
